UNITED STATES PATENT OFFICE.

ALBERT RANDALL WELLS, OF SLINFOLD MANOR, ENGLAND.

PAVING BLOCK.

Application filed October 5, 1925. Serial No. 60,558.

To all whom it may concern:

Be it known that I, ALBERT RANDALL WELLS, a subject of the King of Great Britain, residing at Slinfold Manor, in the 5 county of Sussex, England, have invented certain new and useful Improvements in Paving Blocks, of which the following is a specification.

This invention relates to paving blocks 10 and has for its objects to provide such devices which are self setting, require no jointing, can be lifted from position at will and which have non-slipping wearing surfaces.

In general paving blocks made according 15 to the invention are manufactured of any material suitable for paving and comprise a body having an upper wearing surface the sides being formed with alternate projections and recesses so arranged that when in 20 position the projections on one block come in the recesses of a number of adjacent and similarly shaped blocks. Each block is formed with a number of projecting feet upon which it stands, suitable padding material 25 preferably being located beneath the feet and similar padding material being disposed between the projections of one block and the recesses of adjacent blocks. A key hole is provided at the centre of each block 30 extending therethrough and the wearing surface is formed with concentric ridges or beads to prevent slipping the beads being discontinuous where required to form drainage grooves.

35 A preferred form of paving block made according to the invention is shewn on the drawing in which:—

Fig. 1 is a plan view of a block with a number of adjacent and similar blocks.

40 Fig. 2 is a sectional elevation on the line 2—2 Fig. 1.

Fig. 3 is a section of the surface on the line 3—3 Fig. 1.

45 Fig. 4 is a sectional elevation on the line 4—4 Fig. 1 and

Fig. 5 is a perspective view to a smaller scale shewing the under side of the block.

In the drawing the body of the block as 50 shewn has a substantially cylindrical centre portion with three lateral projecting portions at equiangular distances apart, forming between them three recessed or re-entrant portions.

Each block has six feet 6 projecting from 55 the bottom thereof and each foot has a pad 7 attached to it upon which it stands. Other

pads 8 are inserted upon three sides of each block which come into contact with unpadded portions of adjacent blocks as shewn in Fig. 1. The pads are preferably made 60 of material such as bituminous felt.

It will be seen therefore that each block makes six padded contacts with the surface on which it stands and six padded contacts with the six surrounding and adjacent 65 blocks. The block is thus held immovably interlocked, all pressure owing to the particular form of the blocks tending to keep their relative positions exactly true.

The parts 7 and 8 are preferably of bi- 70 tuminous felt or other similar or suitable material.

9 is a key hole passing through the centre 75 of each block by which it can be lifted and the surface of each block is beaded concentrically as shewn at 10 to form a nonslip- 80 ping surface. The beads are discontinuous, and crossed by drainage grooves 11, see Figs. 1 and 3, which open into the key hole 9 or the space between the blocks bounded by 85 three adjacent projecting portions.

What I claim and desire to secure by Letters Patent of the United States of America is:—

1. A paving block comprising a body hav- 85 ing an upper wearing surface, a number of feet projecting from the under surface of the body, pads of a material such as bitumi- 90 nous felt beneath the said feet, alternate lateral projections and recesses for co-opera- 95 tion with recesses and projections respec- 100 tively of similar surrounding and adjacent blocks, pads of a material such as bitumi- 105 nous felt upon alternate side faces, and a key hole extending from the upper wearing 110 surface to the under surface for the pur- 115 poses set forth.

2. A paving block comprising a body hav- 100 ing an upper wearing surface, a number of feet projecting from the under surface of the body, pads of a material such as bitumi- 105 nous felt beneath the said feet, alternate lateral projections and recesses for co-opera- 110 tion with recesses and projections respec- 115 tively of similar surrounding and adjacent blocks, pads of a material such as bitumi- 120 nous felt upon alternate side faces, a key hole extending from the upper wearing sur- 125 face to the under surface and beadings 130 formed in the upper wearing surface for the purposes set forth.

3. A paving block comprising a body having

an upper wearing surface, a number of feet projecting from the under surface of the body, pads of a material such as bituminous felt beneath the said feet, alternate lateral 5 projections and recesses for co-operation with recesses and projections respectively of similar surrounding and adjacent blocks, pads of a material such as bituminous felt upon alternate side faces, a key hole extending from the upper wearing surface to the under surface and discontinuous beadings 10 formed in the upper wearing surface for the purposes set forth.

4. A paving block comprising a body 15 formed from a substantially cylindrical centre portion with three similar lateral projecting portions at equiangular distances apart leaving between them three

similar lateral recessed portions, adapted to receive projecting portions of similar surrounding and adjacent blocks, the said body having an upper wearing surface, a number of feet projecting from the under surface of the body, pads of a material such as bituminous felt beneath the said feet, pads 20 of a material such as bituminous felt upon alternate side faces, a key hole extending from the upper wearing surface to the under surface, concentric discontinuous beadings 25 formed in the upper wearing surface around the opening to the key hole and drainage grooves between the discontinuous beadings 30 for the purposes set forth.

In witness whereof I affix my signature.

ALBERT RANDALL WELLS.
